UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed January 16, 1926. Serial No. 16,135. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein—

The dress is distinguished by the arrangement of ornamental tucks arranged to present parallel stripes at the front and a V-shaped ornamental arrangement at the rear. The dress is also distinguished by an ornamental arrangement of pockets wherein a substantially V-shaped appearance is pre-

sented, matching the ornamental arrangement of cuffs having somewhat V-shaped sections at the front.

Figure 1 is a front view of a dress, showing my new design, the same being illustrated on a figure.

Figure 2 is a rear view of the dress shown in Figure 1.

Figure 3 is an enlarged detail fragmentary sectional view through Figure 2 on line 3—3, showing the ornamental arrangement of tucks.

I claim:

The ornamental design for a dress, substantially as shown and described.

TAUBE DAVIS.
